INVENTOR.

Frank H. Gladding,

UNITED STATES PATENT OFFICE.

FRANK H. GLADDING, OF PROVIDENCE, RHODE ISLAND.

IMPROVEMENT IN BUCKLE-FASTENINGS.

Specification forming part of Letters Patent No. 136,151, dated February 25, 1873.

To all whom it may concern:

Be it known that I, FRANK H. GLADDING, of Providence, in the county of Providence and State of Rhode Island, have invented a new and useful Improvement in Buckle-Fastenings; and I do hereby declare that the following specification, taken in connection with the drawing making a part of the same, is a full, clear, and exact description thereof, in which—

Figures 1 and 2 represent the front and back views of my invention. Figs. 3 and 4 are perspective views of the two parts, and Fig. 5 represents my invention as connected by a strap when in use.

My invention consists in forming two plates, to be locked together when in use by a stud or cross-bar passing through their centers, and so arranged that the under plate may act as a spring in securing the lock.

Similar letters of reference indicate corresponding parts.

A, Fig. 3, represents a round plate of metal having a slot cut across its center, and a knob fastened near the outer edge at one end of the slot. It is also provided with two small holes, one on each side of said slot, for the purpose of fastening the stud or cross-bar hereinafter described. B, Fig. 4, represents the back plate, which is cut from its outer edge toward its center, and formed spherical to operate as a spring. At the center of this plate is riveted or soldered a stud with a cross-bar, C, which cross-bar is made with a slot running nearly its whole length, and on its under side it is provided with two projections or teats for fastening into the small holes in plate A.

Instead of soldering or riveting a knob on plate A, the blank plate may be cut with a projection on its edge, as shown by dotted lines on Fig. 1, and turned up at right angle in forming said knob.

In applying my invention on a horse-blanket, I use two sets of plates. On one of the front plates I use a knob, and the other front plate I make plain, as shown on Fig. 5. I also use a washer between these plates, Figs. 1 and 2. It may be cut any desired form or shape, as ornamental. A hole is first made in the blanket, and the cross-bar C passed through. The washer is now applied. The plate A is then slipped on, and, by pressing the two plates A and B together, the stud or cross-bar C may be turned through the slot in A, and locked by its two projections or teats springing into the holes made in A for that purpose. The two sets of plates being thus fastened on the blanket, one end of a strap is attached to one of the cross-bars, and in their use the opposite end of the strap is made fast to the knob, in suitable holes through said strap, as represented on Fig. 5.

I am aware that similar knobs and straps are not new. I therefore do not desire to claim them specially as my invention; but

What I do claim is—

The spring-plate B, in connection with the stud or cross-bar C, and in combination with plate A, when constructed to operate as herein described, and for the purpose specified.

FRANK H. GLADDING.
